United States Patent Office.

WILLIAM H. MARTIN, OF BROOKLYN, NEW YORK.

Letters Patent No. 76,219, dated March 31, 1868.

IMPROVEMENT IN METHOD OF CREATING DRAUGHT IN CHIMNEYS BY MEANS OF STEAM.

The Schedule referred to in these Letters Patent and making part of the same.

TO ALL WHOM IT MAY CONCERN:

Be it known that I, WILLIAM H. MARTIN, of the city of Brooklyn, in the county of Kings, and State of New York, have invented certain new and useful Improvements in the Method of Creating Draught in Chimneys by Means of a Blast of Steam; and I do hereby declare the following to be a full, clear, and exact description of the same, reference being had to the annexed drawing, making part of this specification, in which—

Figure 1 is a plain elevation, and

Figure 2 a vertical section of a common smoke-pipe or chimney with my improvement applied thereto, and Figures 3, 4, and 5 are detailed parts of my invention, to be hereinafter described.

It has long been the practice to introduce a jet of steam in the smoke-stack or chimney of a steam-boiler to increase the draught of the furnace, but the application, so far as I am informed, has hitherto been so imperfectly made that the best attainable result has not been accomplished.

The object of my improvement, therefore, is to more effectually and equally apply the blast of steam in the chimney or smoke-stack, to secure, if possible, the maximum advantage of its application.

This object I accomplish by delivering the steam through an orifice, or what I style a "blast-head," constructed substantially in the following manner and form; that is to say, I first make a cup of the form substantially as shown by *a*; into this cup I screw a hub, *b*, with a flange or disk, *c*, made thereon, and with a hole, *d*, drilled in the axis thereof, to meet similar holes, *e e e*, drilled transversely therein, through which the steam is to pass. The flange *c* is made a little less in diameter than the inside diameter of the top of the cup, leaving an opening all around the flange, between it and the cup, through which the steam is forced in a circular volume up the chimney, carrying the air above it, and inducing a draught through the furnace below.

Fig. 5 shows a plane elevation of the hub and flange, and the transverse holes *e e* in perspective, and fig. 4 shows an inverted view of the said hub, with the hole in the centre, and the transverse holes in dotted lines, and fig. 3 shows a top view of the chimney or smoke-stack, and the manner in which the blast-head is secured therein, said blast-head being attached to a steam-pipe, *f*, leading to the boiler, from whence the steam is drawn to create the blast, and consequent draught in the furnace.

Having now described the nature and extent of my improvement, I claim—

In combination with a smoke-stack or chimney, the blast-head *a*, constructed substantially as described, so as to deliver the steam in said stack in a circular volume or volumes, substantially as set forth.

WM. H. MARTIN.
